UNITED STATES PATENT OFFICE.

GENEVIEVE HEILNER, OF NEW YORK, N. Y.

CORSET.

1,311,444.

Specification of Letters Patent.

Patented July 29, 1919.

Application filed May 16, 1919. Serial No. 297,512.

To all whom it may concern:

Be it known that I, GENEVIEVE HEILNER, a citizen of the United States, residing at New York, in the county of New York and State 5 of New York, have invented a new and useful Improvement in Corsets; and I do hereby declare the following, when taken in connection with the accompanying drawings and the characters of reference marked 10 thereon, to be a full, clear, and exact description of the same, and which said drawings constitute part of this application, and represent, in—

Figure 1 a perspective view of a corset 15 constructed in accordance with my invention.

Fig. 2 a side view of one-half of the corset.

This invention relates to an improvement in corsets, and particularly to bust-reducing 20 corsets; the object being to provide a corset of usual construction with means for reducing the bust; and the invention consists in the construction as hereinafter described and particularly recited in the claims.

In carrying out my invention I employ a 25 corset 3 of any approved cut and construction, preferably a so-called short corset. Superimposed upon the upper edge of the front and side sections of the corset are bust-reducing sections 4 and 5. These are preferably formed from elastic fabric, although that is not necessary. The lower edges of the bust-reducing sections are secured to the 30 upper edges of the front and side sections 6 and 7 of the corset, and the front binders 8 and 9 extend to the upper edges of the bust-reducing sections, the forward edges of which are inclined upwardly and rearwardly. The rear edges of the bust-reducing 35 sections are secured to the forward edges of the back sections 10, which are made somewhat longer than usual for this pur-

pose. The forward edges of the bust-reducing sections are preferably connected by lacings 11, so as to permit of more or less adjustment; but these edges may be hooked together or otherwise secured as desired. Preferably, and as herein shown, the corset is also provided with shoulder straps 12 and 13, one end of each being secured to the back 45 sections of the corset and the opposite ends engaged by buckles 14 secured to loops 15 attached to the upper edges of the bust-reducing sections near their forward edges. These bust-reducing sections may be drawn 50 as tightly as required, and may be adjusted independently of the adjustment of the corset proper.

I claim:—

1. The combination with a corset having 55 its back section extended vertically above the upper edges of the front and side sections, and elastic bust-reducing sections permanently secured to the upper edges of the said front and side sections and to the forward edge of the extensions of the back sections.

2. The combination with a corset having 60 its front and side sections cut away at their upper ends and the back section extended 65 vertically above the upper edges of said front and side sections, and elastic bust-reducing sections permanently secured to the upper edges of the said front and side sections and to the forward edges of the extensions of the back sections.

In testimony whereof, I have signed this specification in the presence of two subscribing witnesses.

GENEVIEVE HEILNER.

Witnesses:

D. SQUIRE,
JULIUS HEILNER.
